CLAIM

The ornamental design for a cycle advertising display, as shown and described.

DESCRIPTION

FIG. 1 is a Front elevational view of a cycle advertising display showing my new design.

FIG. 2 is a Left side elevational view thereof, the right side being a mirror image.

FIG. 3 is a top plan view thereof; and,

FIG. 4 is a side elevational view thereof.

The broken lines are shown for illustrative purposes only and form no part of the claimed design.
